UNITED STATES PATENT OFFICE

JAMES V. CRICHTON, OF PHILADELPHIA, PENNSYLVANIA

FOLDING TABLE

Application filed February 25, 1931. Serial No. 518,127.

This invention relates to folding tables, and it has reference more particularly to card tables wherein the legs are foldable against the underside of the table top.

5 In folding card tables, as heretofore constructed diagonal knuckle joint braces were ordinarily employed to hold the legs extended. Such knuckle braces were prone to yield upon accidental contact with them and 10 were therefore not reliable as a means to secure the legs and to prevent collapse of the tables.

15 My invention is in the main directed toward overcoming the drawback just mentioned through pivotal provisions, in connection with tables of the indicated sort, whereby, as the legs are swung to extended position, they are securely locked against accidental collapse while supporting the table 20 top in firm stability.

25 My invention is further concerned with means operative in conjunction with the provisions aforesaid to hold the legs from displacement when collapsed upon the underside of the table top.

Still other objects and attendant advantages of this invention will be manifest from the following detailed description of the attached drawing, wherein Fig. I is a plan 30 view of the underside of a folding table conveniently embodying my invention, with the table legs collapsed.

Fig. II is a fragmentary view of a corner portion of the underside of the table showing 35 on a larger scale and in greater detail the novel means by which the legs are connected to the table top.

Fig. III is a fragmentary section taken as indicated by the arrows III—III in Fig. II.

40 Fig. IV is a view corresponding to Fig. III but with the table leg extended; and,

Fig. V is a fragmentary detail sectional view, taken as indicated by the arrows V—V in Fig. I, and showing the means provided 45 for yieldingly holding the legs against displacement when collapsed against the table top.

With more specific reference to these illustrations, the numeral 10 comprehensively 50 designates the top of the table, which, in

the present instance is square and which may be of any desired construction. To the underside of the table top 10 are secured angularly flanged, cast corner pieces 11 with integrally formed depending studs 12. Pivotally connected to a bearing boss 13 on one of the flanges 14 of each corner piece 11 as well as to a bearing lug 15 spaced from the said flange, is a yoke member 16. Centrally of its cross bar 17, the yoke member 16 has a boss 18 wherein the tubular leg indicated at 19 is afforded limited sliding guidance for capacity to engage over the stud 12, when extended as in Fig. IV. A compression spring 20 interposed between the boss 18 of the guide member 16 and a head 21 around the upper end of the leg 19, serves to maintain the latter yieldingly interlocked with the stud 12, as in Fig. IV, when the table is in use.

From Fig. II it will be noted that the springs 20 also serve, when the legs 19 are folded down, to maintain the upper ends of the latter in contact with the sides of the studs 12 and thus tend to hold the legs 19 horizontal. To assist the springs 20 in the function just described and to insure the legs 19 against the possibility of displacement when folded, spring clips 22 are secured to the corner pieces 11 adjacent the bearings lugs 15 to yieldingly engage the legs at their free ends after the manner best illustrated in Fig. V.

In setting up the table, the legs 19 are pulled out of the holding clips 22 and swung at right angles to the table top 10 about their pivotal connections with the corner pieces 11, incident to which they are automatically urged longitudinally upward by means of the springs 20 so that their upper ends engage over and interlock with the studs 12 as in Fig. IV.

When so interlocked with the studs 12, it is evident that the legs 19 are effectively secured against the possibility of accidental collapse, and the top 10 supported in firm stability as long as the table is used. To fold the table, the legs 19 are first pulled in opposition to the springs 20 until they clear the studs 12 of the corner pieces 11, and thereupon swung down about their piv-

otal connections against the top 10 to re-engage the holding clips 22.

If desired or found more convenient in practice, the legs 19, instead of being made tubular as herein illustrated, may be of solid construction with axial sockets at their upper ends to cooperate with the studs 12.

Having thus described my invention, I claim:

- 10 1. In a folding table, the combination with the top of an angularly-flanged corner piece embodying a depending stud, means integral with said corner piece affording pivotal support for a yoke member having a tubular boss, and a leg having sliding guidance in said boss with capacity to engage over or be restrained in contact with the side of the stud aforesaid.
- 20 2. In a folding table, the combination with the top of an angularly-flanged corner piece embodying a depending stud, means integral with said corner piece affording pivotal support for a yoke member having a tubular boss, and a leg having limited sliding guidance in the boss for engagement over the depending stud to lock said leg in vertical position or to be sustained horizontally by contact with the side of said stud.
- 30 3. In a folding table, the combination with the top of an angularly-flanged corner piece embodying a depending stud, a bearing boss in one of the angular flanges and a spaced bearing lug integral with said corner piece to jointly afford pivotal support for an associated yoke member embodying a tubular boss, and a leg having limited sliding guidance in the tubular boss with means engageable over the depending stud to lock said leg in vertical position or to be sustained horizontal by contact with the side of such stud.
- 40 4. In a folding table, the combination with the top of angularly-flanged corner pieces each embodying a depending stud, a bearing boss in one of the angular flanges and a spaced bearing lug integral with each said corner piece to jointly afford pivotal support for yoke members embodying tubular bosses, and tubular legs with flanged heads afforded limited guidance in the respectively associated tubular bosses for capacity to engage over the studs to lock said legs in vertical position or to be sustained horizontal by contact with the sides thereof.
- 50 5. In a folding table, the combination with the top of angularly-flanged corner pieces each embodying a depending stud, a bearing boss in one of the angular flanges and a spaced bearing lug integral with each said corner piece to jointly afford pivotal support for yoke members embodying tubular bosses, legs with flange heads having sliding guidance in the tubular bosses, and a spring under compression intermediate each boss and leg head flange whereby the legs may be respec-

tively locked in vertical position over the depending studs or maintained horizontally in folded position against the underside of the table top.

6. In a folding table, the combination with the top of angularly-flanged corner pieces each embodying a depending stud, a bearing boss in one of the angular flanges and a spaced bearing lug integral with each said corner piece to jointly afford pivotal support for yoke members embodying tubular bosses, legs with flange heads having sliding guidance in the tubular bosses, a spring under compression intermediate each boss and leg head flange whereby the legs may be individually locked in vertical position over the depending studs or maintained horizontally in folded position against the underside of the table top, and a spring clip on each corner piece to yieldingly engage the respective legs at their free ends when moved into horizontal position.

In testimony whereof, I have hereunto signed my name at Philadelphia, Pennsylvania, this 21st day of February, 1931.

JAMES V. CRICHTON.
